UNITED STATES PATENT OFFICE

106,861

DESIGN FOR A NAIL DRIVE ANCHOR

Paul C. Dellinger, Lancaster, Pa., assignor to
U. S. Expansion Bolt Company, New York,
N. Y., a corporation of New York

Application August 13, 1937, Serial No. 71,069

Term of patent 14 years

To all whom it may concern:

Be it known that I, Paul C. Dellinger, a citizen of the United States, residing at Lancaster, in the county of Lancaster and State of Pennsylvania, have invented a new, original, and ornamental Design for a Nail Drive Anchor, of which the following is a specification, reference being had to the accompanying drawing, forming part thereof, wherein:

Figure 1 is a view in elevation of a nail drive anchor showing my new design;

Fig. 2 is a top plan view thereof; and

Figs. 3 and 4 are perspective views thereof looking from opposite sides,

The design consists of a plurality of circumferential ribs extending for the major portion of the length of each of three jaws of a split tubular sleeve at one end of which is a pair of oppositely directed lobular flanges, the ribs on each jaw being staggered with respect to the ribs on the adjacent jaws.

I claim:

The ornamental design for a nail drive anchor, as shown and described.

PAUL C. DELLINGER.
